Primary Examiner — Amy C Wierenga(74) *Attorney, Agent, or Firm* — Perkins Coie LLP**CLAIM**

The ornamental design for a gasket, as shown and described.

DESCRIPTION

FIG. 1 is a perspective view of a gasket of the present application;

FIG. 2 is a top elevation view thereof;

FIG. 3 is a bottom elevation view thereof;

FIG. 4 is a right elevation view thereof;

FIG. 5 is a left elevation view thereof;

FIG. 6 is a front elevation view thereof; and,

FIG. 7 is a back elevation view thereof.
